UNITED STATES PATENT OFFICE.

GEORGE W. KELLY, OF ELIZABETH, NEW JERSEY.

BRAKE JAW OR FORK.

1,165,514.

Specification of Letters Patent. Patented Dec. 28, 1915.

Application filed September 20, 1915. Serial No. 51,553.

To all whom it may concern:

Be it known that I, GEORGE W. KELLY, a citizen of the United States, and a resident of Elizabeth, in the county of Union and State of New Jersey, have invented certain new and useful Improvements in Brake Jaws or Forks, of which the following is a specification.

The invention pertains more particularly to improvements in brake-forks or jaws such as are used on street and railway cars, and the like, in connection with the brake-beams and rods.

One purpose of the invention is to provide a special rod connection permitting of the convenient use of a malleable jaw and a rod secured thereto in accordance with the special features of my invention whereby the rod and jaw may be very conveniently and permanently connected together and held against either axial or longitudinal movement with relation to each other.

In accordance with my invention I provide a malleable or other metal jaw having a body portion and jaw members, and within said body portion I provide an opening whose walls are tapered and countersunk laterally at opposite sides and within this opening I apply the end of a rod, while in a heated state, and upset said end of the rod so that it fills said opening and cannot be withdrawn therefrom or rotate therein, leaving the rod at the outer end of the body portion of the jaw in substantially its initial condition, my purpose being to obviate the formation of a shoulder on the rod at the outer end of the body portion of the jaw and to avoid the inconvenience and expense of forming such shoulder.

My invention will be fully understood from the detailed description hereinafter presented, reference being had to the accompanying drawings, in which:

Figure 1 is a longitudinal section through a grip-die and jaw held therein, the connecting rod being shown as having its hot end extended through the opening in the body portion of the jaw, and the end-portion of a plunger-tool of a forging machine being illustrated preparatory to passing between the members of the jaw and upsetting the end of the rod extending through the opening in the body portion of the jaw; Fig. 2 is a longitudinal section, partly broken away, taken on the dotted line 2-2 of Fig.

3, through the jaw and rod shown in their connected state; Fig. 3 is a longitudinal section, partly broken away, through the jaw and connecting-rod taken on the dotted line 3-3 of Fig. 2; Fig. 4 is a transverse section through the same, taken on the dotted line 4-4 of Fig. 3, and Fig. 5 is a side elevation of the jaw and a portion of its connecting rod.

In the drawings 10 designates the fork or jaw, 11 the rod of wrought metal secured thereto, 12 a grip-die of forging machine of usual character and therefore not shown, and 13 a plunger-tool of said machine.

The fork or jaw 10 comprises integrally, a body-portion 14 and parallel corresponding jaw-members 15 extending therefrom and longitudinally therewith and formed with alined holes 16 for the customary bolt or pivot pin, not shown. The body 14 of the fork or jaw 10 has extending through it a longitudinal hole 17 of special formation and the adjacent end of the rod 11 has thereon a head 18 formed within and filling said hole and permanently connecting the fork or jaw and said rod together, and the essence of my invention resides more especially in the said formations securing the fork or jaw and rod together and which are very advantageous. The hole 17 extending through the body 14 of the fork or jaw is substantially circular at its outer end and snugly conforms to the cross-section or diameter of the rod 11, and inwardly from its outer end the walls of said hole 17 diverge, the opposite walls 19 having a gradual and continuous divergence to the inner end of the hole 17 between the facing sides of the jaw-members 15, as shown in Fig. 3, and the other opposite walls 20 of said hole having a more abrupt divergence nearly to the inner end thereof and then converging toward each other on curved lines, as at 21, Fig. 2, and then again diverging, as at 22, whereat transverse ribs or lugs 23 are formed at opposite sides of the inner end of the hole 17 and overhang the same, leaving said hole with two opposite tapered sides and two opposite tapered and countersunk sides at whose inner end edges are the said transverse ribs or lugs 23. The ribs or lugs 23 at the inner end edges of the sides 19 of the hole 17 are connected by integral portions 24 of the fork or jaw, as shown in Figs. 3 and 4.

The rod 11 is of wrought metal and appropriate dimensions and its inner end which is to be secured to the fork or jaw 10 is heated to the forging or upsetting stage 5 and inserted through the hole 17 and projected far enough beyond the same to afford sufficient metal for the formation of the head 18, and thereafter said end of said rod is upset to entirely fill the hole 17, the head 10 18 thus being formed and engaging all the wall surfaces of said hole 17 including the diverging surfaces extending upon the ribs or lugs 23.

I do not confine my invention to any special means for upsetting the end of the rod 11 within the hole 17 of the fork or jaw but I recommend that this operation be performed on a forging machine, with the fork or jaw and rod held in a grip-die 12 in position to be acted on by a plunger-tool 13, said tool being adapted to pass between the jaw-members 15 and directly engage the heated end of the rod 11.

When the end of the rod 11 has been upset 25 to fill the hole 17 and form the head 18, it is obvious that due to the special formation of said hole and the presence of said head therein, the fork or jaw and rod cannot be pulled apart or separated from each other. 30 The hole 17 inwardly from its outer end is of oval formation or of greater width across one diameter than across the other diameter and this results in the rod 11 and fork or jaw 10 being held against turning action 35 one upon the other. The connection described of the rod 11 with the fork or jaw 10 is of very great strength and efficiency and one which may be produced with entire convenience and in a thoroughly practical manner.

I may call attention to the fact that in carrying out my invention, there being no shoulder required on the rod 11 at the outer end of the hole 17, the die 12 may closely engage the entire outer surfaces of the body portion 14 and adjacent surfaces of the jaw-members 15 and thus efficiently back and support the fork or jaw during the upsetting of the end of the rod 11 on a forging 45 machine, which upsetting may be performed by one operation or stroke of the machine.

What I claim as my invention and desire to secure by Letters Patent, is—

1. A brake fork or jaw and a rod, said 55 fork comprising a body portion and jaw members integral therewith and said body portion having extending through it a longitudinal hole whose walls intermediate their end portions are tapered and countersunk laterally, and said rod at one end being upset within and filling said hole.

2. A brake fork or jaw and a rod, said 60 fork comprising a body portion and jaw members integral therewith and said body portion having extending through it a lon-

gitudinal hole whose walls intermediate their end portions are tapered and countersunk laterally, and said rod at one end being upset within and filling said hole, and said body portion at opposite sides of the inner 70 end of said hole having integrally therewith ribs or lugs which overhang said hole and upon the facing edges of which portions of the upset end of the rod extend.

3. A brake fork or jaw and a rod, said 75 fork comprising a body portion and jaw members integral therewith and said body portion having extending through it a longitudinal hole which is greater in one cross diameter than in the other and has at two 80 opposite sides substantially continuous slightly diverging walls and at its other opposite sides more abruptly diverging walls continued by converging wall surfaces forming lateral countersunk portions within said 85 hole, and said rod at one end being upset within and filling said hole.

4. A brake fork or jaw and a rod, said 90 fork comprising a body portion and jaw members integral therewith and said body portion having extending through it a longitudinal hole which is greater in one cross diameter than in the other and has at two opposite sides substantially continuous 95 slightly diverging walls and at its other opposite sides more abruptly diverging walls continued by converging wall surfaces forming lateral countersunk portions within said hole, and said rod at one end being upset within and filling said hole, and said body 100 portion at opposite sides of the inner end of said hole having integrally therewith ribs or lugs which overhang said hole and upon the facing edges of which portions of the up- 105 set end of the rod extend.

5. A brake fork or jaw and a rod, said 110 fork comprising a body portion and jaw members integral therewith and said body portion having extending through it a longitudinal hole whose walls intermediate their end portions are tapered and countersunk laterally, and said rod at one end being upset within and filling said hole, and said hole inwardly from its outer end being greater 115 in one cross diameter than in the other.

6. A brake fork or jaw and a rod, said 120 fork comprising a body portion and jaw members integral therewith and said body portion having extending through it a longitudinal hole having opposite walls which present tapered and laterally countersunk surfaces, and said rod at one end being upset within and filling said hole.

7. A brake fork or jaw and a rod, said 125 fork comprising a body portion and jaw members integral therewith and said body portion having extending through it a longitudinal hole having opposite walls which present tapered and laterally countersunk surfaces, and said rod at one end being up- 130

set within and filling said hole, and said body portion at opposite sides of the inner end of said hole having integrally therewith ribs or lugs which overhang said hole and 5 upon the facing edges of which portions of the upset end of the rod extend.

Signed at Elizabeth, in the county of

Union, and State of New Jersey, this 16th day of September, A. D. 1915.

GEORGE W. KELLY.
